CLOTHESLINE SUPPORT

Ernest E. Hansquine, Montreal, Quebec, Canada

Application July 30, 1948, Serial No. 41,455

2 Claims. (Cl. 211—119.17)

1

This invention relates to clotheslines, and more particularly to a vertically adjustable supporting means for the pulley of a clothesline arranged so that said pulley may be lowered in order to secure clothes to the line or to remove clothes therefrom, whereby the task of hanging clothes is greatly facilitated.

A main object of the invention is to provide a novel and improved vertically adjustable support for the pulley of a clothesline, said support being very simple in construction, easy to manipulate, and enabling the user to readily lower the pulley in order to place clothes on the line or to remove clothes therefrom, thereby eliminating the necessity of employing a step-ladder or other means to reach the line and reducing the hazards incident to the use of the step-ladder or other means, as well as eliminating the need for stretching to reach the line.

A further object of the invention is to provide an improved vertically adjustable clothesline pulley support which is easy to install, simple to operate, and which is particularly suitable for installation on porches or the like, whereby the pulley may be normally positioned adjacent the porch ceiling but may be readily lowered to a convenient height for the placement of clothes on the line or for the removal of clothes therefrom, and wherein the line may be reached without overexertion and without requiring the use of a step-ladder or other raised support.

Further objects and advantages of the invention will become apparent from the following description and claims, and from the accompanying drawings, wherein:

Figure 1 is a side elevational view of an adjustable clothesline pulley support device constructed in accordance with the present invention.

Figure 2 is a front elevational view of the clothesline pulley and support therefor shown in Figure 1.

Figure 3 is an enlarged top plan view of the clothesline pulley and support therefor illustrated in Figures 1 and 2.

Figure 4 is an enlarged cross-sectional detail view taken on line 4—4 of Figure 1.

Figure 5 is a cross-sectional detail view taken on line 5—5 of Figure 4.

Figure 6 is a side elevational view of the clothesline pulley and support device of Figure 1 with the pulley in a lowered position.

Referring to the drawings, 11 designates a vertical bar member formed with threads 12 and 13 at its top and bottom ends. Designated at 14 is a screw eye fastened in the wall 15 of a building,

such as the wall of a porch or the like, the screw eye 14 being located at an elevated position, such as adjacent the ceiling of the porch. The eye of the screw 14 is engaged over the top end portion of bar member 11 and is rigidly secured to said rod member by top and bottom nuts 16 and 17 engaged on the threads 12. Designated at 18 is another screw eye fastened in wall 15, and engaged over the lower end portion of bar member 11 as shown in Figure 1. Designated at 19 is a bracket member engaged on the rod member 11 in sub-adjacent screw eye 18. The screw eye 18 and bracket member 19 are rigidly clamped together on the bar member 11 by top and bottom nuts 20 and 21 engaged on the threads 13.

Bracket member 19 is provided with a vertical upstanding flange 22 which is formed with a vertical notch 23 in its intermediate portion. Designated at 24 is a vertical rod member and secured in said rod member at spaced intervals thereon are a plurality of headed projections 25, such as headed screws threaded into the rod member. The clothesline pulley is shown at 26 and is rotatably supported in a frame 27, the axle 25 of the pulley being shown at 28 and passing transversely through said frame. The frame 27 is formed with a rearwardly extending yoke portion 29 merging into an arm portion 30, said arm portion terminating at its rear end in a yoke 31 through which the vertical bar member 11 slidably passes. Journaled between the ends of the arms of yoke 31 and engaging the bar member 11 with rolling contact thereon is a roller 32 which has an annularly grooved periphery receiving said bar member 11. The intermediate portion of arm 30 is annularly grooved, as shown at 33, and is rotatively encircled at annular groove 33 by the eye of a screw eye 34 fastened in the top end of vertical rod member 24. The clothesline, shown at 35, passes over the pulley 26.

Normally the pulley 26 is supported in an elevated position by the engagement of the lowermost headed projection 25 in the notch 23 of bracket member 19. When it is desired to lower the pulley 26 to obtain access to the line 35 for the purpose of hanging clothes on the line or removing clothes therefrom, rod member 24 is grasped at its bottom end and elevated slightly to disengage said lowermost projection 25 from the notch 23. The rod member 24 is then swung outwardly and allowed to descend until the pulley 26 has been lowered to a convenient height. The pulley 26 is supported in this lowered position by engaging one of the upper headed projections 25 in the bracket notch 23. To return the pulley

26 to its normal elevated position the rod member 24 is lifted and the lowermost projection 25 is engaged in the notch 23, thereby restoring the parts to their initial positions.

It is thus seen that when it is desired to place clothes on the line or to remove clothes from the line, it is merely necessary to lower rod member 24 in the manner above described, whereby access to the line may be had without stretching or straining, and without the necessity of employing a step-ladder or other support for reaching the line. This eliminates the risk of injury incident to standing on a step-ladder or other support while hanging or removing clothes, and also reduces the time and labor required for the clothes hanging and removing operation.

While a specific embodiment of an adjustable clothesline pulley support has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A clothesline raising and lowering device comprising at least two attaching elements projecting in vertical spaced relation from a supporting surface, a vertically disposed bar fixedly secured to said attaching elements, a bracket having one end fixedly secured to said bar, an upstanding flange provided with a notch on the other end of said bracket, a frame arranged transversely of and spaced from said bar and having one end rollably supported for travel upwardly and downwardly along said bar, a rod arranged in spaced relation with respect to said bar and having one end mounted on said frame intermediate its ends for swinging movement therearound, and a plurality of headed projections positioned in spaced relation along said rod and each selectively engageable with a notch on said flange to thereby hold said frame.

2. A clothesline raising and lowering device comprising at least two screw eyes projecting in

vertical spaced relation from a supporting surface, a vertically disposed bar having the upper end extending through and projecting beyond one of said screw eyes and having the lower end extending through and projecting beyond the other of said screw eyes, each of the projecting end portions of said bar being externally threaded, a pair of nuts in threaded engagement with each threaded projecting end portion of said bar and receiving therebetween the adjacent screw eye, a bracket having one end fixedly secured to said bar, an upstanding flange provided with a notch on the other end of said bracket, a frame arranged transversely of and spaced from said bar and having one end rollably supported for travel upwardly and downwardly along said bar between said pairs of nuts, a rod arranged in spaced relation with respect to said bar and having one end mounted on said frame intermediate its ends for swinging movement therearound, and a plurality of headed projections positioned in spaced relation along said rod and each selectively engageable with the notch on said flange to thereby hold said frame.

ERNEST E. HANSQUINE.
